Mullicent W. Pitt

BY

Arthur Potts Marr

ATTORNEY

UNITED STATES PATENT OFFICE.

MILICENT WALDRON PITT, OF NEW YORK, N. Y.

FOUNTAIN SPRAY.

Application filed March 11, 1924. Serial No. 698,426.

The device, the subject of this invention, is intended as a spray or syringe and has for its principal object, the construction of a device of this nature, wherein treatments 5 may be administered or had, of added anti-septic value; and another object is to provide means whereby a pressure can be applied to the force of the water or other solution being administered, a pressure 10 greater than that obtained through gravity flow devices.

With these and other objects in view, the following is what I consider the best means of carrying out this invention and the accompanying drawing should be referred to for a complete understanding of the specification which follows.

In the drawings:—

Fig. 1 is an elevation, partly in section, 20 and shows my complete device.

Fig. 2 is a plug or stopper, which may be used with the container.

Fig. 3 is an enlarged view, partly in section and shows the pressure pump.

Similar reference numerals indicate like 25 parts in all the figures where they appear.

The container shown at 5 should be of glass and of any desirable size, though I prefer that my container should be of generally oval shape and should hold about three 30 quarts.

The container may be considered a glass bottle, having flat sides and a screw-threaded neck or mouth is indicated at 6. Screw-threaded within the mouth 5 is a fitting consisting of a screw-threaded plug 7 and parts attached and supported thereby. This fitting may be formed of hard rubber or other suitable material, and is provided with a 35 passage 8 extending therethrough.

Screw-threaded into one wall of the passage 8 is a plug 9 which may be provided with a clamping wire 10, the clamping wire serving to support a disk or block 11 of soap 40 or of a medicating mixture formed in tablet shape and quite readily dissolvable.

I provide another passage as shown at 12 in the member that I have called a fitting and formed integral with the fitting or se- 45 cured thereto and communicating with the

passage 12 is a pump 13. This pump may be an ordinary air pump and is intended for the purpose of forcing air into the container 5 and upon the liquid therein.

A glass tube 14, secured in the plug and 55 fitting 7, extends almost to the bottom of the container 5 and it is through this glass tube that the liquid will pass as it is ejected from the container by the air pressure therein.

The end of the fitting to which I have previously referred terminates in a discharge passage 15 of reduced diameter and to this reduced portion 15, I attach a tube 16 which may be an ordinary rubber tube of any desirable length. In the tube I may insert a controlling valve 17 and to the free end of the tube, I may attach an applicator 18 of any desired shape or size. The applicator 18 should be formed of glass as should other 60 applicators used with this device, as such are far more sanitary than applicators of other materials.

When the valve 17 closes, air pressure may be built up within the container 5 by means 75 of the pump 13 and thereafter, when the valve 17 is open, the liquid within the container 5 will pass through the tube 14, into the passage 8 and washing past the disk 11 will dissolve this disk, carrying its 80 medication through the tube 16 and applicator 18.

As before stated, the size of parts may be changed, the shape thereof may be varied and other modifications made within the 85 scope of the appended claim.

At 19 I show a plug or stopper which may be employed with the container 5 as a substitute for the fitting previously described. This plug or stopper will be employed when it is desired to transport the container filled from place to place or when it is desired to use the container as a hot water bottle.

Having carefully and fully described my 95 invention what I claim and desire to obtain is:—

A fountain spray comprising a container, a fitting screw-threaded into the neck of 100 said container and provided with a liquid

passage therethrough, a piston pump having its cylinder formed integral with said fitting, a plug screw-threaded into said fitting and at right angles to the liquid passage and a clamping device secured to said plug and adapted to support a tablet in said liquid passage, in combination with an ap-

plicator, a tube connecting said applicator with said fitting and a valve in said tube for controlling the flow therethrough.

Signed at the city, county and State of New York, 1924.

M. WALDRON PITT.
